PERRIN B. WHITNEY, OF NEW YORK, N. Y., ASSIGNOR TO MESINGER-WHITNEY ELECTRIC COMPANY, INC., OF NEW YORK, N. Y.

COMBINED LAMP AND HORN.

1,157,744.

Specification of Letters Patent. Patented Oct. 26, 1915.

Application filed April 8, 1915. Serial No. 20,069.

To all whom it may concern:

Be it known that I, PERRIN B. WHITNEY, a citizen of the United States, and a resident of New York city, in the county of Bronx, and State of New York, have invented a certain new and Improved Combined Lamp and Horn, of which the following is a specification.

This invention relates to a combined lamp and horn adapted to form an attachment for motorcycles, automobiles and similar vehicles, and in which the shell of the lamp is so constituted as to form a support for the casing of the horn. In this way compactness is insured, the attachment of the device to the vehicle frame is simplified, and the shell of the light is made to assume the additional function of constituting a resonating chamber for the horn.

In the accompanying drawing: Figure 1 is a perspective view of a combined lamp and horn embodying my invention; Fig. 2 a plan, and Fig. 3 a longitudinal section thereof.

The shell or casing 10 of the lamp is shown to be generally of rounded or paraboloidal form and contains reflector 11, and one or more light bulbs 12, the wires 13 of which pass outwardly through an axially arranged socket 14. Shell 10 is furnished with a pair of apertured lugs 15, to which are secured by pins 16, the shanks of a bail 17, having a screw stem 18, by means of which the device is adapted to be attached to the frame of a motor cycle, automobile or similar vehicle.

A substantial portion of shell 10, does not

partake of its paraboloidal form, but is flattened or disk-shaped as indicated at 19, the flattened portion being reinforced by a circumferential groove 20. From disk-shaped section 19 there extend outwardly at right angles, a plurality of short posts 21, which are deflected at an angle to the axis of the shell. To posts 21 is secured a cylindrical casing 22, the bottom of which is spaced from the disk-shaped section 19 and is arranged in parallelism therewith. This casing may be closed by a lid or cover 23, and constitutes the container for a horn or similar sounding device, shown to consist of an electrically actuated vibrator 24 the wires 25 of which extend outwardly through apertures 26 of lid 23.

It will be seen that by the construction described, the lamp as well as the sounder are conjointly secured to the vehicle body by one and the same attaching means, so that simplicity of construction is insured, a multiplicity of parts is avoided and space is economized. So also the shell of the lamp is so disposed relatively to the casing containing the sounder, that it will constitute a resonating chamber for the latter, by means of which the efficiency of the sounder is greatly augmented.

I claim:

A device of the character described comprising a shell, an inclosed light, a casing mounted upon the shell and spaced therefrom, and a sounder within the casing, the shell constituting a resonating chamber for the sounders.

PERRIN B. WHITNEY.
